UNITED STATES PATENT OFFICE.

LUTHER P. FRIESTEDT, OF CHICAGO, ILLINOIS.

METALLIC RAILWAY-TIE.

932,115.

Specification of Letters Patent.

Patented Aug. 24, 1909.

Application filed March 30, 1907. Serial No. 365,514.

To all whom it may concern:

Be it known that I, LUTHER P. FRIESTEDT, citizen of the United States, residing at Chicago, in the county of Cook and State 5 of Illinois, have invented certain new and useful Improvements in Metallic Railway-Ties, of which the following is a specification.

This invention relates to metallic railway ties to be used as a substitute for the ordinary wood cross tie; and has for its object to provide a tie that will embody all of the requirements necessary in a device of this character, as will be hereinafter set forth in detail.

15 The growing scarcity of timber suitable for ties makes it apparent that a practical substitute must be provided.

A further object, therefore, is not only to provide a substitute as to material, but also 20 one that will embody all the advantages of the wood tie with none of its disadvantages.

In the drawing, Figure 1 is a longitudinal section of a metal tie embodying the improved features, the track-rail being shown in 25 place. Fig. 2 is a transverse section on line 2, Fig. 1. Fig. 3 is a view in perspective; and Fig. 4 is a modification.

The tie is ordinarily composed of a metal-beam rolled or otherwise made into the desired integral form.

A may represent the integral structure as a whole, which consists of the flat top-part 5 and the double angle side flanges or wings 6 and 7. The top-part of the tie or sleeper 35 forms the seating surface on which the track-rails 8 rest. The angular sides anchor the tie in the earth or other material with which the road is ballasted.

The flanges 6 form the upper part of the 40 double angle sides and extend outward and downward in a diagonal plane to the junction 9 with the flanges 7, which extend inward and downward in a diagonal plane corresponding to the angle at which the 45 flanges 6 are disposed, that is, approximately forty five degrees. This construction provides an inverted channel or hollow tie, the flanged sides forming a double arch support with a rigid bracing effect, as best 50 shown in Fig. 2.

The tie is split inward from its respective ends on each side as at 10. This feature provides for the ends 11 of the top-part being bent downward at any desired angle (Figs. 1 55 and 2) in partially closing the ends of the tie

to prevent the ballast or filling from working out and at the same time afford an additional brace and anchorage in maintaining a level track. This hollow tie may be filled with concrete or any composition thereof, but 60 ordinarily the usual ballast will be sufficient for all practical purposes as the tie is open on the under side.

The top-part is provided (Fig. 3) with a number of apertures 12 for the insertion of 65 the rail spikes 13 in the operation of securing the track rails to the ties. The initial apertures are somewhat less in length than the greatest diameter of the spike so that the point end of the spike will just enter and be 70 held in position to be driven, as best shown in Fig. 1. The slits 14 are cut through the top-part and extend longitudinally on two sides of the apertures 12 and open thereinto. These slits are of a greater length than the 75 side dimensions of the apertures and provide tongues 15 which are free to bend downward from the pressure of the spikes when driven into place.

The rail fastening spikes 13 are provided 80 with corrugations 16 on two opposite sides, as shown in Fig. 1. When the spikes are driven in the operation of securing the rails in place, the free ends of the tongues 15 are 85 bent downward by contact with the corrugated sides and remain in engagement therewith. By this means the spikes are firmly locked in place against working out from any of the usual causes. The spikes may be readily removed by turning them around far 90 enough to disengage the heads 17 from the flanged-base 18 of the track rails and bring the smooth sides of the spikes in line with the tongues 15 and free the same from their locking engagement when they can be easily 95 slipped out. The spikes are held just as firmly in place as though driven into wood and are more easily drawn out without bending the same. This form of construction affords a double arched base or truss on the respective sides of the compound type and which will successfully resist the heavy load and compression strains to which cross-ties are subjected. A tie of this form will be sufficiently rigid for all practical purposes and 100 at the same time yielding just enough to conform to all changing conditions. It can be economically rolled from a bar or billet in any length that is practical and then cut up into tie lengths.

105

110

Fig. 4 is a modification in that it presents curved or rounded sides instead of angular sides.

Having thus described my invention, what I claim is—

1. A railway-tie having a flat top-part provided with angle anchor or holding flanges, a part of which extends downward and outward in a diagonal plane and another part 10 downward and inward in a corresponding plane, leaving the under side of the tie open.
2. A railway-tie of the class described, having apertures formed in the top thereof and slits extending along two sides of said apertures and forming tongues in line with said slits, said tongues being adapted to be depressed in locking a fastening object.
3. A railway-tie having apertures formed in the top side thereof and tongues on opposite sides of said apertures, whereby when the rail fastening spikes are inserted said tongues are depressed and the spikes locked in place.
4. In a railway-tie comprising an integral structure and having apertures formed in the top thereof with slits extending backward from opposite sides of said apertures providing tongue parts free at one end, and spikes serrated on two sides and adapted to depress the free end of said tongues in the operation

of securing the track-rails and locking the 30 spikes against accidental displacement.

5. An integral metal railway tie comprising a top portion and side portions which extend outwardly at an angle, and then inwardly at an angle, said tie being open at the 35 bottom and the opposite ends of the top of the tie being downturned.

6. A metallic railway tie having an integral spring tongue formed in its upper surface in combination with a spike having a 40 serrated face adapted to be engaged by said integral spring tongue, and an integral member carried by the tie and bearing against the opposite face of said spike.

7. A metallic railway tie, having a pair of 45 integral spring tongues struck therefrom and located in the upper face thereof, in combination with a spike having two of its sides serrated to be engaged by said spring tongues, the remaining faces of said spike 50 being smooth.

In testimony whereof I have signed my name to this specification in the presence of two subscribing witnesses.

LUTHER P. FRIESTEDT.
